UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,123,577.

Specification of Letters Patent.

Patented Jan. 5, 1915.

Application filed July 9, 1907. Serial No. 382,898.

To all whom it may concern:

Be it known that I, LANSING ONDERDONK, a citizen of the United States, residing at New York, in the county of New York, 5 State of New York, have invented certain new and useful Improvements in Looper-Operating Mechanisms for Sewing-Machines, of which the following is a description, reference being had to the accompanying drawing, and to the letters and figures of reference marked thereon.

My invention relates to new and useful improvements in sewing machines and more especially to the looper operating mechanism therefor.

The object of my invention is to provide a looper operating mechanism which shall be positive in its movements and simple in construction.

20 My invention consists in the parts, improvements and arrangements hereinafter shown, described and set forth in the claims.

In the drawings which show by way of 25 illustration one embodiment of my invention, Figure 1 is a front elevation of a sewing machine, having my improved looper operating mechanism applied thereto, certain parts being broken away for the sake of clearness. Fig. 2 is a bottom plan view of a sewing machine showing the looper operating mechanism, a portion of the feeding mechanism being broken away for the sake of clearness. Fig. 3 is an end view of 30 a portion of the sewing machine, showing the looper operating mechanism. Fig. 4 is a detail top plan view showing the looper and its operating lever and in dotted lines the same parts in a different position. Fig. 35 40 5 is a detail perspective view of my preferred form of looper.

The bed plate 1 has rising therefrom, an overhanging arm 2, carrying the usual needle mechanism at its forward end. The 45 main shaft 3, mounted in the overhanging arm, is rotated by suitable means and power is transmitted from said main shaft 3 to a shaft 4, mounted underneath the work support or bed plate 1, by a belt 5. Said belt engages suitable pulleys 6 and 7 mounted upon the shafts 3 and 4, respectively.

The looper is carried by an upright looper support 7, which is mounted in a 55 bracket 8 secured to the under side of the

bed plate. Said bracket 8 is provided with forwardly projecting arms 9 and 10. The looper support 7 extends through the arms 9 and 10 and a collar 11 fastened to said support, serves as a supporting means for 60 said looper support. A nut 12 together with a washer 13 on the lower end of the support 7, prevents the looper support 7 from moving vertically in the bracket 8. The looper support 7 is formed with a recess 65 in its upper end in which is set the shank of the looper 14. The looper shank 14 is bent laterally and upwardly and thence curved as at 15 to lie substantially in the arc of a circle the center of which is the 70 axis of the looper support 7. The bracket for supporting the looper is so disposed that the looper in its movements, moves outside of the needle 16 as shown in Fig. 4.

The looper support 7 has an arm 17 secured thereto between the bracket arms 9 and 10. Said arm 17 is pivoted at 18 to a link 19 which in turn is pivoted at 20 to a lever 21 fulcrumed upon a stud 22 formed on a depending lug 23, carried by the bed 75 plate 1. The opposite end of the arm 21 carries a ball stud 24 which is connected by a link 25 to a ball stud 26 carried by a crank arm 27 on the end of the shaft 4. As the shaft 4 is rotated, the crank arm 27 through 80 the link 25, will vibrate the lever 21 about its fulcrum 22. The disposition of the lever 21, and the looper is such that as the lever is vibrated from a position shown in dotted lines in Fig. 4 to the position shown in 85 full lines, the pivotal connection 20 between said lever and the link 19 will cross a line passing through the fulcrum point 22 of the lever and the axis of the pivotal connection 17 between the lever and the link 90 19 (see dotted line $x-x$, Fig. 4). When the lever 21 is in the position shown in dotted line in Fig. 4, the looper is at the rear end of its stroke and the point of the looper stands slightly in rear of the needle path. 95 As the needle rises to throw out its loop, the looper moves forward into said loop as shown in full lines in Fig. 4. The looper is given an extended dwell at the forward end of its stroke, owing to the fact that the 100 pivot point 20 between the link 19 and the lever 21, moves across the line $x-x$, shown in Fig. 4. As the pivotal connection 20 approaches this line, the speed of the looper decreases until said looper is brought to a 110

stand-still and the movement of the pivotal connection 20 beyond the line $x-x$ practically gives little or no movement to the looper, and therefore, the extended dwell at the forward end of the stroke of the looper is secured.

When the looper stands at the forward end of its stroke as shown in Fig. 4, the 10 looper thread 28 extends from the eye of the looper to the previous stitch, and owing to the curve of the looper, the looper thread is held at one side of the needle path, so that the needle may pass with certainty between the looper thread and the 15 body of the looper. After the needle has entered the looper thread loop the looper is then retracted quickly to the rear end of its stroke.

From the above description, it will be 20 noted that I have provided a looper which moves in a single path in a horizontal plane, and that said looper moves quickly forward into the needle loop, where it is given an extended dwell, while the needle rises and descends again into the looper thread loop 25 and after the needle has entered the looper thread loop, said looper is moved readily to shed the previous needle loop and into such position as to enter the new loop 30 thrown out by the needle.

It will be noted that the position of the 35 crank 27 on the shaft 4, relative to the connecting link 25 between said shaft and the lever 21, is such that when the looper is at the forward end of its stroke, said crank is passing the dead center on the side of the shaft opposite the position of the lever 21, and, therefore, said crank is at this time 40 passing its slow center and the necessary dwell in the throw of the crank at this time is added to the dwell caused by the pivot point 18 crossing the line $x-x$. On the other hand, the crank 27 when the loop is at the rear end of its stroke is passing its 45 quick dead center, and the rapid movement imparted to the link at this time is added to the rapid movements caused by the position of the link 19 relative to the looper carrier and the operating lever 21.

Having thus particularly described my 50 invention, what I claim as new and desire to secure by Letters Patent, is:

1. A sewing machine including in combination, a work support, a rotary shaft 55 mounted beneath the work support, a needle, a looper, means for supporting said looper, whereby the same moves about a fixed axis substantially parallel with the needle path, said looper being curved about said fixed 60 axis as a center, means for operating said looper from said shaft beneath the work support, including a lever, devices for oscillating said lever from said shaft, and a link connecting said lever to said looper, said 65 link and lever being so disposed as to move

into and out of alignment, said looper being at the forward end of its stroke when said link and lever are in alignment.

2. A sewing machine including in combination, a work support, an overhanging arm, a main shaft mounted on the overhanging arm, a rotary shaft mounted beneath the work support, means for transmitting motion from the main shaft to said last named shaft, a needle, a curved looper, 70 means for supporting said looper, whereby the same moves about a fixed axis substantially parallel with the needle path, and means for operating said looper, including a lever, means for connecting said lever to 75 said rotary shaft, and a link connecting said lever to said looper, said link and lever being so disposed as to move into and out of alignment whereby to give an extended dwell to the looper at the forward end of its 80 stroke.

3. A sewing machine including in combination, a work support, a rotary shaft beneath the work support, a needle, a curved looper, means for supporting said looper 90 whereby the same moves about a fixed axis substantially parallel with the needle path, and means for operating said looper including a lever pivoted to the under side of the work support, and moving about an 95 axis parallel to the axis of the looper, a link for connecting said lever to said rotary shaft, and a second link for connecting said lever to said looper, said second link and said lever being so disposed as to give 100 an extended dwell to the looper at the forward end of its stroke.

4. A sewing machine including in combination, a work support, a rotary shaft mounted beneath the same, a needle, a looper moving in a plane substantially at right angles to the path of the needle, a bracket supporting said looper, a lever pivoted to the underside of said work support and moving in a plane substantially parallel thereto, a link connecting said lever to said looper and means for connecting said lever to said rotary shaft, said link and lever being so disposed as to be substantially in line 110 when the looper is at the forward end of its stroke.

5. A sewing machine including in combination a work support, a rotary shaft beneath the same, a looper, a looper support therefor, a bracket having projecting arms in which said looper is mounted, a projecting arm carried by said looper support, a lever pivoted to the under side of the work support, a link connecting said lever to the projecting arm on said looper support, and means between said lever and said rotary shaft, for oscillating said lever.

6. A sewing machine including in combination a work support, a rotary shaft mounted beneath said work support, a crank 120

carried by the forward end of said rotary shaft, a needle, a looper moving in a plane substantially at right angles to the path of the needle, a support for said looper, a lever 5 pivoted to the under side of said work support, and connected to said looper, and a link connecting said lever and said crank on the rotary shaft.

7. A sewing machine, including in combination a work support, a rotary shaft mounted beneath said work support and having one end thereof located centrally of said work support, a crank arm carried by the end of said rotary shaft, a needle, a 10 looper moving in a plane substantially at

right angles to the path of the needle, a support for said looper, a lever pivoted to the under side of said work support, means for connecting one end of said lever to said looper, a ball stud carried by the opposite end of said lever and a link connecting said ball stud with the crank arm on said rotary shaft. 20

In testimony whereof I affix my signature, in presence of two witnesses.
